UNITED STATES PATENT OFFICE.

FRANÇOIS JURICINEC, OF PARIS, FRANCE.

MONKEY WRENCH.

Application filed September 27, 1926, Serial No. 138,047, and in France October 3, 1925.

My invention relates to monkey wrenches of the type which, when actuated in view of rotating the part to be screwed down or to be unscrewed such as a bolt, a nut, a tube and the like provide automatically for the tightening of the jaws whereby the bolt, nut, tube, or other similar part is securely held and can be released subsequently only by means of a special movement adapted to provide this release.

My improved monkey wrench comprises primarily a lever to the end of which is secured a spindle bearing a pinion meshing with a rack borne by the body of one of the jaws or preferably with two racks borne respectively by the bodies of the two jaws. In the latter case the two racks are disposed so as to move in opposite directions when the pinion rotates. This arrangement provides a greater relative displacement of the two jaws for a given rotation of the pinion whereby a given wrench can be used for a wider range of diameters of the parts to be tightened.

Moreover the bodies or stems of the two jaws are enclosed in a substantially parallelepipedic casing inside which they can slide with a slight friction whereby no play can arise either longitudinally or transversely.

A form of execution of my invention is described hereinbelow by way of example and illustrated on appended drawings whereof:

Fig. 1 is a side view of the wrench when not working.

Fig. 2 is a partly sectional side view, the jaws being shown removed apart before closing over a nut or the like.

Fig. 3 is a partly sectional front view of the same wrench.

Figs. 4 and 5 are side views of slightly modified wrenches.

The wrench shown on Figs. 1 to 3 comprises a controlling lever 1 bearing at its inner end a spindle 2 to which is keyed the pinion 3. A parallelepipedic casing 4 is pivotally secured to the same spindle and is suitably cut open at its top end 5. This casing contains the two stems 6 and 7 forming respectively the lower and upper jaws 8 and 9 which project beyond the top 5 of the casing 4. The stems 6 and 7 are respectively provided with

the racks 10 and 11, both of which mesh with the pinion 3 at diametrically opposite points thereof.

The wrench works as follows. When a part is to be taken hold of, the lever 1 is rotated in the direction of the arrow 12 whereby the jaws 8 and 9 are removed away from each other until they are sufficiently spaced to allow the said part to be taken hold of. For tightening the latter, the lever is rotated in the opposite direction, that of the arrow 13; thus the part is tightened, whilst the two jaws are brought closer and press more tightly against the part to be tightened by the rotation of the lever 1.

For unscrewing or releasing a part the wrench is turned back to front so that the side shown as the upper side on Figs. 1 and 2 becomes the lower side. Then the part to be unscrewed being secured between the jaws 8 and 9, the lever 1 is rotated in the direction which causes the jaws to move towards each other.

The stems 6 and 7 being enclosed in the casing 4 cannot show any play in the plane either of Figs. 1 and 2 or of Fig. 3.

In the modified wrench shown on Fig. 4, the stem 6 extends beyond and below the casing 4 and forms the rod 14 whereby an easier handling is provided. This arrangement does away with the necessity of turning the tool back to front for unscrewing. It is sufficient for this, to push the rod 14 in the proper direction.

The modified form shown on Fig. 5 is specially adapted for tubes. The jaws 8 and 9 are oblique with reference to the stems 6 and 7 and the uncurved inner side 15 at the jaws is toothed or striated.

What I claim is:

1. In a monkey wrench comprising a casing, two jaws sliding in said casing, a common pinion between said jaws, a rack borne by each jaw and meshing with the common pinion, the combination of a forked control lever, the inner ends of which pass on either side of the casing and a spindle to which the common pinion is keyed passing through the casing and fixed to the said inner ends of the control lever.

2. In a monkey wrench comprising a casing, two jaws sliding in said casing, a com-

mon pinion between said jaws, a rack borne by each jaw and meshing with the common pinion, the combination of a forked control lever the inner ends of which pass on either

5 side of the casing, a spindle to which the common pinion is keyed passing through the casing and fixed to the said inner ends of the

control lever, and an extension of one of the jaws substantially parallel to the control lever.

10 In testimony whereof I have signed my name to this specification.

FRANÇOIS JURICINEC.
